COMBINED TAPE CASSETTE HOLDER AND PICTURE FRAME

Michael H. Barkman, Palatine, Ill., assignor to Wabash
Tape Corporation, Des Plaines, Ill.

Filed Apr. 3, 1972, Ser. No. 240,886

Term of patent 7 years

Int. Cl. D3—99
U.S. Cl. D87—1 D

Fig.1

Fig.2

Fig.3

Fig. 4

Fig. 5

Fig. 6

FIG. 1 is an interior elevational view of a combined tape cassette holder and picture frame showing my new design in an open position;

FIG. 2 is a top plan view thereof;

FIG. 3 is an elevational view looking from the left of FIG. 1;

FIG. 4 is a view looking from the rear of FIG. 1;

FIG. 5 is an elevational view looking from the left of FIG. 4; and

FIG. 6 is a sectional view taken on the line 6-6 of FIG. 5.

I claim:

The ornamental design for a combined tape cassette holder and picture frame, as shown.
